METHOD OF SANDBLAST CARVING

Stephen Chruma, Kansas City, Kans.

Application February 3, 1941, Serial No. 377,121

5 Claims. (Cl. 41—39)

This invention relates to improvements in the method of sand blast carving and has particular reference to shape carving of stone, granite, marble, etc. wherein relief designing is produced by undercutting portions of a design to imitate actual structures.

Heretofore sand blasting has been used to produce relief carving but not to produce undercut work, which requires the use of chisel and mallet. This hand cutting is very slow and because of the cost is prohibitive for use in designing most monuments.

The present invention contemplates the use of the sand blast process to produce the desired undercut relief work, at a rapid rate and at a cost far less than the cost of tool undercutting.

In carrying out my method the surface to be carved is covered with a sheet of compressible and yielding material which is secured in position by an adhesive. The design to be produced is cut through the coating sheet to present a plurality of separate sheet sections.

Other objects of this invention is the method of shape-carving granite or the like by the sand blast process to produce undercut relief designs at a much more rapid rate than has been possible with the old methods now in use.

The drawing forming a part of this application shows a typical design and the various steps involving carrying out this method of sand blast carving, and like characters designate similar parts throughout the several views.

Figure 1 is a sectional view of a block of granite or any other hard material suitable for sand blast carving having a surface to be carved, covered with a sheet of yieldable material.

Fig. 2 is a view similar to that shown in Fig. 1 whereon the desired design has been cut through the yieldable sheet covering and a portion of the sheet peeled off to permit sand blasting of the exposed granite surface.

Fig. 3 is a further showing of the block with the gun nozzle in position to direct the sand at right angles to the surface to be carved to produce a substantially vertical wall adjacent the surface to be undercut.

Fig. 4 is another view of the granite block showing the gun nozzle positioned to direct the sand to form an undercut below the covered surface of the block.

Fig. 5 is a plan view of the block with the yieldable cover sheet positioned thereon and having the design cut therethrough.

Fig. 6 is a plan view of the block with the desired design formed in its surface portion.

Fig. 7 is a cross-sectional view taken on line VII—VII of Fig. 6.

Referring to the drawing, the numeral 10 designates a block of granite, marble, stone or any other relatively hard material adapted to be

carved or cut away by the action of sand blasting. By the term "sand blasting" is meant the abrasion of a surface by forcing a current of air, carrying an abrasive thereagainst. The abrasive being sand, carborundum, steel or any other material of greater hardness than the material to be carved. The surface 12 to be carved is shown as of planar shape, however it might be of any other form without interfering with the method of carving. The surface to be carved is covered with a sheet or coat of yielding material, a soft rubber, gelatinous material, etc., which is substantially immune to the sand blast, due to its compressibility when engaged by the rapidly moving particles of abrasive. This surface covering may be of an adhesive nature suitable to adhere to the surface to be carved or it may be secured thereto by means of an applied adhesive.

The desired design 14 is now cut through the sheet covering as shown in Fig. 5. The slits 16 constituting a line drawing of the design segregates the various portions 18, 22, 24, 26, 28, 30, 32, 34, 36, 38 and 40 so that they may be separately and selectively peeled from the surface to be carved, so as to expose only the part to be carved while other parts remain covered to facilitate proper carving. The covering strip 18 is first removed and an outline groove 42 is sand blasted to the desired depth.

In order to properly carve the design such as shown it is necessary that the undercut portions be directed toward a common center and it is therefore found best practice to first carve the outer portions and work toward said common center. After the outline groove 42 has been carved it will be considered that the cover portion 26 is next removed to permit the formation of one of the outside petals of the rose design shown. The sand blast gun nozzle 44 through which the mixture of abrasive and air under pressure is delivered to the work is now directed substantially vertically to the surface to be carved to produce a wall 46 in register with the edge of the adjacent cover sheet beneath which an undercut is to be formed in the granite block.

The formation of the vertically disposed wall 46 in alignment with the adjacent cover sheet portion is very important in that it makes possible the undercutting of the block at this point without interfering with the adherence of the surface covering of the block to the surface to be carved. After the formation of wall 46 the sand blast gun nozzle can be positioned as shown in Fig. 4 to direct the abrasive material obliquely to the surface to be carved and in the direction of the wall 46 to form an undercut 48. This undercut can be produced to any desired depth and will extend beneath the sheet-protected face of the block.

Should the operator attempt to undercut before

producing the vertical wall 46 the abrasive particles would be directed to the joint between the cover sheet and the surface of the block thus tending to separate the sheet from the block and mutilating the surface of the block thus exposed. With the wall 46 formed the particles of abrasive will be directed downwardly and inwardly against wall 46 and will not interfere with the position of the sheet covering of the block.

It will be noted that the surface 59 will represent the upper surface of the outside rose petal while the surface 52 of the undercut will represent the under side of one of the second row of petals. This same operation is repeated by successively removing cover portions 24, 22, 20, 38, and 28. The operator can now remove sheet cover section 36 to form a vertical wall adjacent the cover portion 40 so as to permit undercutting therebeneath. Likewise cover sections 34, 32, and 30 are successively removed to permit formation of the remaining second row of petals.

The center section of the sheet covering is now removed and the surface sand blasted to produce the central recess 54. After the entire covering for the design has been removed the operator may further sand blast the design to produce the desired rounded edges of the petals. That portion of the cover sheet outside the design is now removed and the surface carving is complete. It is quite apparent that other designs might require outwardly directed undercutting or in some instances the direction of undercut might be varied in the same design.

It is quite apparent that the principal requirement in this method of sand blast carving is that a substantially vertical wall be first produced in the body of the block to be carved in order to make it possible to produce the undercut. As stated above heretofore sand blasting designs of this character have been carried out without any undercuts due to the fact that they could not be produced by any of the then known methods.

With this type of sand blast carving wherein the component particles of the design are more nearly simulated the appearance is greatly improved due to the shades and shadows produced which more nearly resemble those of the actual thing being depicted.

Undercutting on designs of this character has been accomplished by means of chisels and mallet, however this type of work is slow and tedious and is too expensive for commercial use in the construction of monuments. While I have shown, by one design, wherein the present method is used, however its application to practically any of the designs wherein undercut work is desirable it may be used to an advantage.

Having thus described the invention, what is claimed as new and desired to be secured by Letters Patent is:

1. The method of sand blast carving which consists in coating the block surface to be carved with yieldable coating, cutting the design to be carved through said coating to present a plurality of segregated portions of the coating, peeling off one portion of the coating to expose the block surface, directing a sand blast at an acute angle against said exposed surface to form an undercut beneath the adjacent surface coating, then removing the surface covering portion above said undercut and sandblasting the newly exposed surface.

2. The method of sand blast carving which consists in coating the block surface to be carved with yieldable coating, cutting the design to be carved through said coating to present a plurality of segregated portions of the coating, peeling off one portion of the coating to expose the block surface, sand blasting said exposed surface to form a relatively shallow vertical wall in alignment with the adjacent coating portion, sand blasting said block at the juncture of the vertical wall with the adjacent carved surface to form an undercut beneath the adjacent coated surface, successively removing the remaining coating portions and sandblasting the block surface until the design is completely carved.

3. The method of sand blast carving which consists in coating the block surface to be carved with yieldable coating, cutting the design to be carved through said coating to present a plurality of segregated portions of the coating, peeling off one portion of the coating to expose the block surface, sand blasting said exposed surface to form a relatively shallow vertical wall in alignment with the adjacent coating portion, sand blasting said block at the juncture of the vertical wall with the adjacent carved surface to form an undercut beneath the adjacent coated surface, removing the cover coating portion above said undercut to expose the block surface, sand blasting the last exposed surface to reduce the thickness of the block material between said undercut and the block surface thereabove, successively removing the remaining coat portions and carving the exposed surfaces until the design is completely carved.

4. The method of sand blast carving which consists in coating the block surface to be carved with a sheet of yieldable material; cutting the design to be carved through said sheet; peeling the sheet covering from one portion of the surface to be sand blasted; sand blasting said surface by directing the sand at substantially right angles thereto until relatively shallow vertical walls are formed along the edges to be undercut; then directing the sand blast at an acute angle to the surface to be carved and toward said shallow vertical walls, whereby an undercut is formed in the block beneath the then sheet covered portion of the surface, repeating these undercutting steps until the undercutting of all portions of the surface to be carved is completed then removing the remaining sheet covering.

5. The method of sand blast carving which consists in coating the block surface to be carved with yieldable coating, cutting the design to be carved through said coating to present a plurality of segregated portions of the coating, peeling off one portion of the coating to expose the block surface, directing a sand blast at an acute angle against said exposed surface to form an undercut at any desired depth beneath the then sheet covered portion of the surface; peeling off another adjacent portion of the design cover sheet and repeating the sand blasting operations, repeating this peeling off and the sand blasting operations until all the undercutting is completed, then removing the remaining design cover sheet portions and sand blasting these newly uncovered surfaces.
